WHEEL COVER

Paul H. Deesen, Rochester, and Wayne R. Vieira, Warren, Mich., assignors to General Motors Corporation, Detroit, Mich., a corporation of Delaware

Filed Apr. 2, 1964, Ser. No. 79,314

Term of patent 7 years

(Cl. D14—30)

We claim:

The ornamental design for a wheel cover, substantially as shown.
